G. S. GATCHELL.
PRESSER FOOT FOR SEWING MACHINES.
APPLICATION FILED OCT. 27, 1917.

1,400,537.

Patented Dec. 20, 1921.

UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

PRESSER-FOOT FOR SEWING-MACHINES.

1,400,537.

Specification of Letters Patent. Patented Dec. 20, 1921.

Application filed October 27, 1917 Serial No. 198,776.

To all whom it may concern:

Be it known that I, GEORGE S. GATCHELL, a citizen of the United States, residing at Roselle Park, in the county of Union and 5 State of New Jersey, have invented certain new and useful Improvements in Presser-Feet for Sewing-Machines, of which the following is a specification, reference being had therein to the accompanying drawings.

10 This invention relates to sewing machines more particularly of the type adapted to join and cover the raw edges of cut knit goods in one operation as disclosed in my copending application Serial No. 185,446, 15 filed August 10, 1917. Machines of the above type commonly employ a presser-foot having spaced toes and trimming knives adapted to trim off upturned marginal portions of material passing into the space between said toes; the trimmings being deflected to one side by a chute or guard so that they will not interfere with the action 20 of the stitch-forming instrumentalities.

In prior machines of the type above referred to, the spaced presser-foot toes constitute relatively fixed and rigid parts of the presser-foot sole-piece; the flat under surface of which presses the work against the teeth of the feed-dog in the usual manner. In attempting to use such machines 25 for abutting the edge-portion of one ply of material against the superposed edge-portions of two plies of material, as in the formation of the so-called "military shoulder" 30 in knitted underwear, or in the operation of abutting the folded edge of a flattened tubular button-stay strip to the edge of a single ply of body-fabric material at the front of an under-garment, it is found that 35 the two thicknesses of material at one side of the seam serve to lift the presser-foot out of effective relation with the single ply of material at the opposite side of the seam and, as a result, said single ply of material 40 is not fed at the proper speed. As a matter of fact, in military shoulder work for example, the single ply of material forming the main body of the garment is cut crosswise of the wales at the shoulder and 45 the superposed plies of material forming the shoulder strip are cut lengthwise of the wales, thereby rendering it desirable to full 50 in the single ply of material somewhat in order that the finished shoulder seam may 55 be slightly and undistorted.

An object of the present invention is to devise an adjustable presser-foot, for use more particularly in joining and covering the edges of cut knit goods in one operation, which will permit the application of 60 equal or unequal pressures to the material at opposite sides of the center line of seam to secure either a uniform or a relatively differential feeding action at the opposite sides at the center line of the seam regardless of the relative thicknesses of the materials joined.

A further object of the invention is to devise a presser-foot for use in connection with the usual four-motion feed-dog to secure a 70 differential feeding action upon the material at opposite sides of the line of seam formation and in advance of the stitching point.

Another object of the invention is to devise a presser-foot which may be so adjusted as to secure a greater pressure upon the work at the side of the seam where a fulling-in action is desired, so that the material at the opposite side of the seam may be 80 effectively retarded as, for example, by the operator in pulling back upon the work at said opposite side.

A further difficulty encountered in the operation of the prior machines of the class 85 described, results from the tendency of the upturned marginal portions of material which pass between the presser-foot toes to lag behind the portions normally abreast thereof which pass under the presser-foot 90 and are positively fed along by the feed-dog. This lagging tendency of the upturned marginal portions of material often causes a wrinkling or piling up of said marginal portions in advance of the slot or space 95 between the presser-foot toes and the result is that such wrinkles in striking the tips of the presser-foot toes are often pressed or folded down and drawn under the presser-foot, thereby escaping the action of 100 the trimmer. The above described tendency of the upturned edge-portions of material to be drawn under the presser-foot instead of passing into the space between the presser-foot toes is aggravated by the tendency of said edge-portions to curl or lay back upon themselves instead of standing upright in position to pass easily into the guiding slot in the presser-foot.

A further object of the invention, there- 110

fore, is to provide a presser-foot having spaced toe-portions whose tips are so shaped as to scoop up and gradually straighten the edge-portions of material as they pass between said toe-portions on their way to the trimming mechanism.

Further objects of the invention will appear from the following description and claims.

- 10 In the accompanying drawings, Figure 1 is a perspective view of the mechanism adjacent the stitching point of a machine embodying the invention. Fig. 2 is a right side elevation of the presser-foot shown in Fig. 1. 15 Fig. 3 is a left side elevation of the presser-foot. Figs. 4 and 5 are top and bottom plan views, respectively, of the presser-foot. Fig. 6 is a view similar to Fig. 2 with one of the presser-foot sole-pieces removed to show the 20 mechanism of the auxiliary sole-piece. Fig. 7 is a rear elevation of the presser-foot. Fig. 8 is a front elevation of the presser-foot and feed-dog with the work in section at substantially the stitching point and showing 25 the foot adjusted to unequal thicknesses of the material. Fig. 9 is a similar view showing the foot adjusted to equal thicknesses of the material; the material being shown in section at a point even with the front end 30 of the presser-foot and the throat-plate in section at a point farther back but in advance of the trimming knives.

The present invention is preferably embodied in a machine having the constructive 35 features described in my said copending application and including a work-supporting arm 1 which carries the throat-plate 2 and end-cap 3 at its free end. In the head 4 of the machine is journaled the needle-bar 5 carrying the needles n' , n^2 , n^3 and n^4 which coöperate with a thread-carrying looper o to form stitches. Thread-fingers, one of 40 which is shown at 6, oscillate in front of the needles to lay covering threads back-and-forth across the cut edges of the material being stitched. Trimming mechanism comprising a cutting blade 7 and ledger-blade 8 is also provided to trim the upturned marginal portions of material entering the space 45 between the toes of the presser-foot 9 secured to the presser-bar 10. Disposed beneath the throat-plate 2 is the forward feed-dog 11 having its operative work-engaging teeth 12 disposed substantially in a plane and adapted to rise into engagement with the fabric in 50 advance of the needles through apertures in the throat-plate, all as more fully described in my said copending application.

In the preferred embodiment of the invention the presser-foot 9 comprises a supporting block or shank 13 having oppositely disposed flat sides 14 and 15 upon which are pivotally mounted by screw-pins 16 and 17 the similar triangle-shaped sole-piece supports 55 18 and 19. Pivoted by means of the

screw-pin 20 to the forwardly extending lower corner of the sole-piece support 18 is the sole-piece 21 having a heel-portion 22 and a forwardly extending toe-portion 23 which is thinned down at 24 to receive the ledger-blade 8 of the trimming mechanism and terminates in a thickened extremity 26.

The forwardly extending lower corner of the sole-piece support 19 has pivotally secured thereto by means of the screw-pin 27 the sole-piece 28 which extends alongside the sole-piece 21 and, like it, is formed with a heel-portion 29 and a toe-portion 30 the upper side of which is cut away at 31 to afford clearance for the cutting blade 7 of the trimming mechanism; said cutting blade resting yieldingly upon the ledger-blade 8 as more fully disclosed in my said copending application. The sole-piece 28 is formed with a thickened forward extremity 33 and 35 is preferably provided intermediate its ends with a lateral extension 34 which is apertured at 35 to receive the needles n' , n^2 , n^3 and n^4 of the stitch-forming mechanism.

The toe-portions 23 and 30 are spaced 90 apart to receive upturned marginal portions of material which are trimmed off by the knives 7 and 8 and are pressed down into abutting relation by the beveled lower front edge 36 of the lateral extension 34. The triangular sole-piece supports 18 and 19 are formed at their upper corners with slots 37 and 38, respectively, which embrace the respective eccentric pins 39 and 40 formed at the opposite ends of the barrel-shaft 41 journaled within and transversely of the presser-foot shank 13. In the present instance the eccentric pin 39 is disposed above the center of the shaft 41 while the eccentric pin 40 is below the center of said shaft, the object 100 being to secure opposite rocking movements of the sole-piece supports when the shaft 41 is turned in a given direction.

To facilitate manual adjustment of the shaft 41, it is provided with a transverse pin 110 42 whose outwardly bent upper end serves as a finger-piece. Secured to the side of the shank 13 by a screw 43 is an abutment-block 44 in which are threaded upper and lower stop-screws 45 and 46 adapted to be struck 115 by the opposite end-portions of the pin 42 and thereby serving to determine the extreme positions of adjustment of the shaft 41, as shown in Fig. 2. In practice the upper screw 45 may be set to arrest the shaft 41 120 when the sole-pieces 25 and 28 are at the same elevation, as shown in Figs. 7 and 9, and the lower screw 46 may be set to secure a predetermined difference in elevation, as shown in Fig. 8 or in dotted lines in Figs. 2 125 and 3.

In sewing up knitted underwear, most of the seams will be formed by abutting single plies as shown in Figs. 1 and 9. But when the military shoulder seam, for example, is 130

to be formed it is desirable that the necessary adjustment of the presser-foot may be quickly and easily effected. This is accomplished in the present instance by shifting 5 the finger-piece or pin 42 from full to dotted line position, Fig. 2. If it is desired to full in the material at one side of the seam, as for example, the single ply s' in Fig. 8, the shaft 41 is turned so that the 10 sole-piece 21 presses said ply s' more firmly against the feed-dog 11 than the adjacent plies s^2 are pressed by the sole-piece 28. As a result there will be a tendency for the feed-dog to slip relatively to the plies s^2 and fail 15 to feed said plies as fast as the single ply s' . This action may be augmented by the operator in holding back slightly on the ply s^2 while permitting the free advance of the 20 ply s' . When the sole pieces are adjusted to produce a differential feeding action, the work may be fed in a curved path, thus producing a curved seam. Such a seam may be useful either in joining together two abutted edge portions of material or in joining 25 superposed plies of material along a curved path. In presenting work of this character to the machine it is to be understood that the plies s' and s^2 may be advanced to the presser-foot with their edges in abutting 30 relation or the marginal portion of material at one or both sides of the seam may be fed into the slot in the presser-foot and acted upon by the trimmer.

The presser-foot is provided with an auxiliary sole-piece 47 located directly in rear of the needle-aperture 35 and formed with a pair of upstanding ears 48 pivoted at 49 to the lever 50 which is received within the recess 51 at the under side of the presser- 35 foot shank 13 and is pivoted to said shank at 52. An expansion spring 53 housed within a bore 54 in the shank 13 presses downwardly upon the front end of the lever 50 to 40 yieldingly maintain the sole-piece 47 in contact with the work.

In order that the presser-foot toes may scoop up and straighten the marginal portions of material as they pass into the space therebetween, said toes are formed at the 45 upper inner corners of said thickened extremities 26 and 33 with concaved fabric-guiding and lifting surfaces 55 which diverge upwardly, and are convergent and upwardly inclined in the direction of feed. 50 These surfaces act, as shown in Figs. 1 and 9, to lift and gradually straighten the curled or wrinkled edge-portions of material and prevent said portions from folding or being drawn under the toes of the presser- 55 foot and below the plane of the trimmer.

The present construction is obviously susceptible of material modification within the scope of the invention and is not to be understood as limited to the exact form and 60 arrangement of parts shown,

Having thus set forth the nature of the invention, what I claim herein is:—

1. In a sewing machine, the combination with covering stitch-forming mechanism and a trimmer, of presser mechanism including spaced toe-portions between which upturned marginal portions of material are adapted to pass to the trimmer, said toe-portions being formed with upwardly diverging and rearwardly and upwardly inclined 70 guiding surfaces adapted to elevate and straighten curled or wrinkled edge-portions of the material as they pass into the space between the presser-toes.

2. In a sewing machine, in combination, 80 stitch-forming mechanism, a feed-dog, a presser-foot having fabric-engaging portions disposed, respectively, at opposite sides of the line of seam formation and opposed to said feed-dog, said portions being fixed 85 against bodily movement relatively to each other during the operation of the machine, and means for effecting relative bodily adjustment of said portions in a direction transverse to the plane of the feed-dog. 90

3. In a sewing machine, the combination with stitch-forming mechanism and a feed-dog having the usual rising-and-falling and feed-and-return movements, of a presser-foot having distinct sole-pieces opposed to 95 said feed-dog and disposed side-by-side at opposite sides of the line of seam formation, at least one of said sole-pieces being bodily adjustable relatively to the other in a direction transverse to the plane of the work, 100 the adjustment including means for rigidly holding the sole-pieces against relative bodily yielding movement transversely of the plane of the work during the sewing, whereby a differential feeding action at opposite 105 sides of the line of seam is secured.

4. In a sewing machine, the combination with stitch-forming mechanism and a feed-dog having the usual rising-and-falling and feed-and-return movements, of a presser- 110 foot having a shank, sole-piece supports carried by said shank, sole-pieces carried by said supports and opposed to said feed-dog, said sole-pieces being disposed side-by-side and on opposite sides of the line of seam 115 formation, and means for adjusting and fixing the working elevation of at least one of said sole-piece supports to vary the working elevations of said sole-pieces relatively to each other, the adjustment including means for rigidly holding the sole-pieces against relative bodily yielding movement transversely of the plane of the work during the sewing, whereby to secure a differential feeding action at opposite sides of the line 120 125 of seam.

5. A presser-foot for sewing machines comprising, a supporting shank adapted to be secured to a presser-bar, sole-pieces carried by said shank, and means for adjust- 130

- ing the elevations of said sole-pieces simultaneously in opposite directions.
6. A presser-foot for sewing machines comprising, a supporting shank adapted to be secured to a presser-bar, sole-pieces carried by said shank, and eccentric means for adjusting the working elevations of said sole-pieces simultaneously in opposite directions relatively to said shank.
10. 7. A presser-foot for sewing machines comprising a supporting shank, sole-pieces carried by said shank and manually controlled means for adjusting the elevations of said sole-pieces simultaneously in opposite directions.
15. 8. A presser-foot for sewing machines comprising a supporting shank, sole-pieces carried by said shank, manually controlled means for adjusting the elevations of said sole-pieces simultaneously in opposite directions, and stops for determining extreme positions of adjustment of said sole-pieces.
20. 9. In a sewing machine, in combination, a feed-dog, a presser-foot comprising a supporting shank, sole-pieces carried by said shank laterally of the line of seam-formation and each coacting with said feed-dog to feed the material, and a shiftable finger-piece for adjusting the working elevations of at least one of said sole-pieces relatively to said shank.
25. 10. A presser-foot for sewing machines comprising a supporting shank, sole pieces carried by said shank, a shiftable finger-piece for quickly adjusting the working elevation of one of said sole-pieces relatively to said shank, and a stop for determining an extreme position of adjustment of said finger-piece.
30. 40. 11. A presser-foot for sewing machines comprising, a supporting shank, a slotted sole-piece support carried by said shank, a sole-piece carried by said support, and an adjusting shaft having an eccentric portion entering the slot of said sole-piece support for adjusting the latter relatively to said shank.
35. 50. 12. A presser-foot for sewing machines comprising, a supporting shank, slotted sole-piece supports pivoted to opposite sides of said shank, sole-pieces pivoted to said supports, and an adjusting shaft journaled in said shank and having eccentric pins at its extremities entering the slots of said sole-piece supports.
45. 60. 13. A presser-foot having independent supports pivoted thereto, work-engaging sole-sections pivoted to the supports, and means for simultaneously moving the pivoted supports in opposite directions.
55. 65. 14. In combination, a feed-dog, a presser-foot comprising sole sections simultaneously coacting therewith and each adjustable relatively to the other, and means for simultaneously adjusting said sections to thereby vary the relative closeness of approach of the sections to the feed-dog.
15. In combination, independently and pivotally mounted supports, presser-foot sole sections directly pivoted to said supports, and means for simultaneously giving said supports opposite angular movements.
16. In combination, a presser foot shank, independent supports movably carried thereby, means for simultaneously moving said supports in opposite directions, and presser-foot sole sections movably mounted on said supports.
17. In combination, a feed-dog, movable presser-foot sole sections simultaneously coacting therewith, and means for simultaneously adjusting said presser-foot sections in opposite directions relatively to the feed-dog.
18. In a sewing machine, in combination, a feed-dog, presser-foot sole-pieces simultaneously coacting therewith and disposed side-by-side transversely of the line of seam-formation, and adjusting means including a manually controlled sole-piece shifting element connected to said sole-pieces, whereby they may cause the material to be differentially fed, said adjusting means being constructed to hold said sole-pieces against bodily differential vertical movement during their coaction with said feed-dog.
19. In combination, a feed-dog, presser-foot sole sections simultaneously co-operating therewith on opposite sides of the line of seam formation, and means for simultaneously and instantaneously adjusting the relative distances of said sections from the feed-dog, whereby material of the same thickness on opposite sides of the seam line may be differentially fed, and material of different thickness may be uniformly fed.
20. In combination, a presser-foot comprising relatively movable sole sections, a finger-piece for actuating said sections, and adjustable stop means for limiting the extent of such actuation.
21. In combination, a feed-dog, presser-foot sole-sections co-operating therewith and held against bodily differential movement during the action of the feed-dog and means for simultaneously and oppositely adjusting the distances of said sections from the feed-dog.
22. In a sewing machine, the combination with stitch-forming mechanism and a feed-dog having the usual rising-and-falling and feed-and-return movements, of a presser-foot having sole-pieces opposed to said feed-dog and disposed side-by-side, and adjusting means including a manually controlled sole-piece shifting element and connections for relatively varying and rigidly maintaining against differential shift the working elevations of said sole-pieces, whereby

a differential feeding action of the material is secured at different points thereof transversely of the line of seam, to form a curved seam.

- 5 23. In a sewing machine, in combination, a slotted throat-plate, feeding means operating through the slotted throat-plate, a plurality of presser-pieces coöperating with said feeding means above the throat-plate

and fixed against bodily vertical differential movement during the sewing, and adjusting means including a manually operable finger piece for relatively varying the working elevations of said presser-pieces.

In testimony whereof, I have signed my name to this specification.

GEORGE S. GATCHELL.
